BLOWING NOZZLE FOR THE REFINING OF METALS

Josef Auer, Oberhausen, Germany, assignor to Hüttenwerk Oberhausen Aktiengesellschaft, Oberhausen, Germany

Application May 19, 1955, Serial No. 509,670

Claims priority, application Germany May 28, 1954

4 Claims. (Cl. 266—34)

The present invention relates to an apparatus for delivering a fluid into contact with a relatively large body of molten metal and, more particularly, concerns a tuyere or lance for refining metals by introducing a blast from above beneath the surface of a metal bath or by blowing the blast onto the surface of a metal bath. It has been suggested heretofore to surround such a tuyere or lance by a cooling jacket divided into two concentric annular chambers by a thermally insulating wall extending nearly to the mouth of the tuyere or lance, the cooling agent preferably entering the inner annular chamber and being discharged from the outer annular chamber. In this way, the heated cooling water flowing back from the mouth of the tuyere or lance does not increase the temperature of the inflowing water. While this tuyere or lance is characterized by a long service life, it has, however, the drawback that with the customarily employed moderate pressures, only a relatively small quantity of blast can be blown from the tuyere per time unit. This is due to the fact that only a relatively small part of the total volume of the tuyere is available as a central supply pipe for the supply of the blast. Consequently the refining period requires a correspondingly long time. On the other hand, it is not practical to combine a plurality of such water-cooled tuyeres or lances to form a bundle of tuyeres because, aside from the difficulty of handling such a bulky and voluminous structure, the consumption of cooling agent would be unfeasible economically. If it were intended to blow larger quantities of blast per time unit by blowing the blast through the tuyere at a higher pressure, an additional expenditure of energy would be required for the compression of the blast, in addition to the employment of auxiliary devices which would considerably increase the cost of the process. Furthermore, there would exist the danger that a portion of the oxygen would not be taken up by the melt so that the blast is incompletely utilized.

It is, therefore, an object of the present invention to provide a liquid-cooled tuyere or lance which will overcome the above mentioned drawbacks.

It is another object of this invention to provide a liquid-cooled tuyere or lance for refining metals, which will be characterized by a low consumption of cooling water and without being subject to destruction will make it possible per time unit to blow such great quantities of blast that in the time required for refining, the heat losses of the melt by radiation will be comparatively low.

It is another object of this invention to provide a tuyere or lance which will make it possible to bring the blast into contact with the melt in such a way that contact between the reacting constituents will be as intimate as possible to thereby bring about a complete utilization of the blast without excessive loss of metal.

It is a still further object of this invention to provide a tuyere or lance of the type set forth in the preceding paragraph which will be simple in construction, resistant to heat and rough handling and will have a small total cross section only while the cross section available

for the feeding of the blast will be rather large with regard to the cross section of the cooling water jacket.

These and other objects and advantages of the invention will appear more clearly from the following specification in connection with the accompanying drawing in which:

Fig. 1 is a longitudinal section of a tuyere or lance according to the invention, the head of the tuyere being shown partly in elevation and partly in section.

10 Fig. 2 is an end view of the device shown in Fig. 1 when viewing the same in the direction of the arrow II.

Fig. 3 is a cross section of the device taken along the line III—III of Fig. 1.

15 Fig. 4 is a cross section of the device of Fig. 1 taken along the line IV—IV thereof.

General arrangement

The tuyere or lance according to the present invention which is provided with a mouth piece having a plurality of outlet orifices for the blast, is characterized primarily in that the feeding conduit for the blast to the mouth of the tuyere divides the interior of the tuyere or lance into a central supply conduit means or chamber for the feeding of a cooling agent to the mouth of the tuyere, and into an outer substantially coaxial return conduit or chamber of annular cross section for the return of the cooling agent from the feeding conduit for the blast adjacent said mouth. The device according to the invention is furthermore characterized in that the feeding conduit or supply conduit means for the blast is near the mouth of the tuyere or lance provided with openings or passages through which the cooling agent can pass from the said central chamber or supply conduit means to the outer annular chamber or return conduit for the return of the cooling agent. In this way, it is possible, due to the simple and space-saving construction of the device, to supply to the bath surprisingly large quantities of blast per time unit, while the consumption of cooling agent is small and the total cross section of the tuyere is relatively small.

Structural arrangement

Referring now to the drawing in detail, the tuyere or lance shown therein consists primarily of two concentric tubular bodies arranged one within the other. The outer tubular body is designated with the reference numeral 1, whereas the inner tubular body is generally designated with the reference numeral 2. The inner wall surface of the tubular body 1 defines with the opposite wall surface of the inner tubular body a jacket or return conduit 19 for cooling water, which conduit is tightly closed at its upper end by means of a tubular header 4. The tubular body 1 is furthermore provided with a lateral discharge connection 5 for discharging the cooling water from said return conduit. A plate 6 is inserted into the lower end of the tubular body 1 and forms the bottom wall of the tuyere or lance.

According to Fig. 1, the inner tubular body 2 consists of two pipes 7 and 8 placed coaxially one within the other in spaced relationship from each other, thereby confining with each other a feeding conduit of annular cross section for feeding the blast to the mouth of the tuyere or lance. The inner wall surface of the tube 8 defines a central chamber or feeding conduit 3 for conveying the cooling agent to the mouth of the tuyere. Thus, the outer annular chamber or conduit 19 for the return of the cooling agent is separated from the feeding conduit 3 for the cooling agent by the feeding conduit for the blast.

70 The pipe or tube 7 communicates at its upper end with the header 4, while the tube 8 the inner wall surface of which confines the cooling water conveying unit 3 ex-

tends through the header 4. The blast conveying conduit formed by the tubes 7 and 8 extends downwardly up to close to the mouth of the tuyere and becomes wider at its lower end where the tube 7 merges with a pipe 17 of greater cross section so that a distributing chamber 9 is formed. Directly above the bottom plate 6, the distributing chamber 9 is traversed by radial channels 10 separated at the top and sides from said chamber 9 by walls 11 and 12 respectively. Between the channels 10, the distributing chamber 9 extends forward to the bottom plate 6 which at these points is provided with a large number of apertures 13 (Fig. 4). The external side of the tube 7 is provided with guiding or spacer fins 14 (Figs. 1 and 3) which insure that the tube 7 will occupy a substantially concentric position in the tubular body 1. While the blast or refining means may be fed to the distributing chamber directly through the above mentioned feeding conduit defined by the tubes 7 and 8, the refining means may also be fed to the distributing chamber through a plurality of closely adjacently and annularly arranged tubes 15 inserted into the annular chamber or conduit confined by the tubes 7 and 8. The upper ends of said tubes 15 lead into the header 4, while the lower ends of said tubes 15 communicate with the distributing chamber 9.

The blast is conveyed to the header 4 through the feeding pipe 18 and the tubes 16, and through the tubes 15 and the distributing chamber 9 is conveyed to the mouth of the tuyere. Due to the great number of the small apertures 13 in plate 6, the blast is introduced into the metal bath in a large number of small streams like a shower bath. Thus a large reaction surface is provided between the blast emerging from the nozzle and the melt, while the formation of a coherent reaction zone and local overheating of the bath is avoided. Due to the large reaction surface, additionally the heat developed by the refining operation is in a highly satisfactory manner conveyed to the rest of the bath whereby the danger of thermal damage to the tuyere is considerably reduced. Furthermore, the blast brought into a particularly intimate contact with the melt, is quickly absorbed by the same and is utilized completely in a minimum of time.

When annularly arranged blast feeding tubes 15 are employed, those portions of the tubes 7 and 8 which are located between the header 4 and the distributing chamber 9 may be omitted.

The cooling agent, preferably water, is conveyed to the mouth of the tuyere or distributing chamber 9 by the tube 8. If, however, that portion of tube 8 is omitted which is located between parts 4 and 9, the corresponding feeding conduit for the cooling agent is formed by the substantially cylindrical passage confined by the inwardly directed outer wall surface portions of said tubes 15. The cooling agent then flows through the channel 19 and the annular chamber 19 between the tubular body 1 and the tubular body 7 or tube 15, and is discharged from the tuyere through the connection 5. The arrangement of the supply of cooling water along the axis of the tuyere, i. e. within the conduit 3 or within the central chamber confined by the tubes 15, and the discharge of the cooling water along the outside of tube 7 or the outwardly directed wall portions of tubes 15 makes it possible to employ the blast, which passes through the tuyere, as heat insulator for the cooling means passing through the tube 8, and also for cooling the cooling agent discharged through the annular chamber 19. Due to the poor thermal conductivity of the gaseous refining means, the cold cooling means being fed into the tuyere is in a highly satisfactory manner insulated from the hot cooling means being discharged, and reaches the mouth of the tuyere, where the maximum temperature prevails, practically without increase in temperature so that the best possible cooling effect of the mouth of the tuyere is obtained. The employment of an

additional partition of thermally insulating material therefore becomes superfluous.

The heat taken up by the blast from the hot cooling means flowing in the annular chamber 19 is returned to the melt and thus benefits the metal bath while simultaneously the cooling means itself is cooled. This heat exchange can be accentuated by filling the chamber 20 between the tubes 15 and the tube 7 with a good heat conductor as for instance copper.

The cooling effect upon the mouth of the tuyere is increased by the fact that the cooling agent on its way from tube 8 through channels 10 into the annular chamber 19 experiences a sharp change in its direction of flow whereby it is rendered turbulent. Similarly, for obtaining a good cooling effect, the interior surface of the tubular body 1 is roughened to avoid laminar flow of the cooling agent. A turbulent flow of the cooling agent may also be obtained by corrugating the inner surface of the tubular body 1 in longitudinal direction thereof as has been indicated in the lower portion of Fig. 1. As a result thereof the heat emanating surface of the tubular body 1 is increased in an advantageous manner. However, care is to be taken that the corrugations are not so pronounced that dead corners will form in which heated cooling means would be retained.

To protect the immersed portion of the tubular body 1, especially that portion which is adjacent the mouth of the tuyere, from corrosion by the molten bath and the combustion products formed during the refining process, that outer surface of the tubular body 1 which comes into contact with the bath is provided with beads 21 which preferably have grooves therein. When the tuyere or lance is introduced into or withdrawn from the bath, slag sticks to said beads and provides a protective layer 35 on the outside of the tubular body 1. The retaining of a solidified layer of slag on the immersed portion of the tuyere is assisted by the strong cooling action of the enlarged tuyere surface formed by the beads and the grooves therein.

The tuyere or lance according to the invention can therefore be immersed relatively deeply into the bath without damage. By sufficiently deeply immersing the tuyere into the bath and due to the presence of a large reaction surface, the advantage is obtained that the ferrous oxide formed during the refining process has on its way to the surface of the bath sufficient opportunity to give up its oxygen to other ingredients in the iron in the bath such as silicon, carbon, phosphorus etc. Therefore, by employing a tuyere or lance according to the present invention a slag of low iron content is obtained, i. e., a satisfactory yield of iron. Furthermore, in contrast to all heretofore known devices for refining by blowing the blast upon or into the bath, a considerable reduction in the formation of vaporized ferrous oxide in form of the known brown smoke is obtained which fact is due to the relatively great depth of immersion and the avoidance of an overheated reaction zone. Inasmuch as by means of the tuyere according to the invention it is possible with a small consumption of cooling agent and a small total cross section of the tuyere to introduce per time unit large quantities of oxygen into the bath, the refining can be carried out very rapidly so that the heat economy of such refining processes is extremely favorable.

It is, of course, understood that the present invention is, by no means, limited to the particular construction shown in the drawing but also comprises any modifications within the scope of the appended claims.

What I claim is:

1. A tuyere for delivering a gaseous blast into contact with a relatively large body of molten metal, which comprises in combination: first tubular means, a bottom member connected to one end of said tubular means and having an inner surface substantially perpendicular to the longitudinal axis of said tubular means, said tubular means having an outlet at the other end thereof, second

tubular means coaxial with but in spaced relationship to said first tubular means, said second tubular means having one end connected to said bottom member in liquid-tight condition and having the other end thereof arranged for connection with a source of cooling liquid, third tubular means interposed between said first and second tubular means and arranged in spaced relationship thereto, said third tubular means having one end connected to said bottom member in liquid-tight condition and having the other end thereof arranged for connection with a source of gaseous fluid, and tunnel-like passage means partly formed by the inner surface of said bottom member and comprising top and side walls extending in a straight direction substantially perpendicular to the longitudinal axis of said second tubular means through the walls of said second and third tubular means and establishing communication between the interior of said second tubular means and the annular chamber confined by the interior wall of said first tubular means and the exterior wall of said third tubular means, those areas of said bottom member which are confined by said second and third tubular means and located outside said tunnel-like passage means being provided with passages extending through said bottom member and having their axes substantially perpendicular thereto.

2. In combination in a twyer for delivering a gaseous blast into contact with a relatively large body of molten metal: a first tubular member having one end provided with a plate forming the bottom of said first tubular member and having its inner surface substantially perpendicular to the longitudinal axis of said tubular member, said first tubular member having an outlet at its other end, a second tubular member coaxial with said first tubular member and spaced therefrom, said second tubular member having one end connected to the central portion of said bottom in liquid-tight condition and having its other end arranged for connection with a source of cooling liquid, a third tubular member substantially coaxial with and interposed between said first and second tubular members and arranged in spaced relationship thereto, said third tubular member having one end connected to said bottom in liquid-tight condition and having its other end arranged for connection with a source of gaseous fluid, and a plurality of tunnel-like passage means extending in a liquid-tight manner through the walls of said second and third tubular members at the bottom of said first tubular member in radial direction from that end of said second tubular member which is adjacent said bottom for establishing communication between the interior of said second tubular member and the annular chamber confined by the interior wall of said first tubular member and the exterior wall of said third tubular member, said tunnel-like passage means having substantially straight top and side walls and having their inner bottom surface formed by a portion of the inner surface of said plate, those areas of said plate which are confined by said second and third tubular members and the outside of the side walls of said tunnel-like passage means being provided with passages extending through said plate and having their axes substantially parallel to the longitudinal axis of said third tubular member.

3. An apparatus according to claim 2, in which that end portion of said second tubular member which is ad-

jacent the plate forming the bottom of said first tubular member flares outwardly in a bell-shaped manner.

4. A twyer for delivering a gaseous blast into contact with a relatively large body of molten metal, which comprises in combination: first tubular means, a bottom member connected to one end of said tubular means and having a plane inner surface substantially perpendicular to the longitudinal axis of said tubular means, said tubular means having an outlet at the other end thereof, second tubular means coaxial with but in spaced relationship to said first tubular means, said second tubular means having one end connected to said bottom member in liquid-tight condition and having the other end thereof arranged for connection with a source of cooling liquid, third tubular means interposed between said first and second tubular means and arranged in spaced relationship thereto, said third tubular means having a first portion of substantially uniform outer diameter spaced from said bottom member and having a second portion of increased diameter leading from said first portion to said bottom member and being connected thereto in a liquid-tight condition, a plurality of tubes arranged in the annular chamber confined by the inner wall of said first portion of said third tubular means and the outer wall of said second tubular means, one end of each of said tubes leading into the interior of the second portion of said third tubular means and the other end of said tubes being arranged for connection with a source of gaseous fluid, and tunnel-like passage means extending at said bottom member through the walls of said second tubular means and of the second portion of said third tubular means and establishing communication between the interior of said second tubular means and the annular chamber confined by the interior wall of said first tubular means and the exterior wall of said third tubular means, said tunnel-like passage means comprising substantially straight top and side walls and having their inner bottom surface formed by a portion of the plane inner surface of said bottom member, those areas of said bottom member which are confined by the outside wall of said second tubular means and the inside wall of the second portion of said third tubular means and also by the outside of the side walls of said passage means being provided with passages extending through said bottom member and having their axes substantially perpendicular to the inner plane surface thereof.
